UNITED STATES PATENT OFFICE.

GEORGE D. WINTERS, OF RENO, NEVADA.

BARRICADE-ALARM FOR DOORS.

SPECIFICATION forming part of Letters Patent No. 605,366, dated June 7, 1898.

Application filed January 21, 1898. Serial No. 667,456. (No model.)

To all whom it may concern:

Be it known that I, GEORGE D. WINTERS, a citizen of the United States, residing at Reno, in the county of Washoe and State of Nevada, have invented certain new and useful Improvements in Barricade-Alarms for Doors, of which the following is a full, clear, and exact description.

My invention is an improvement in burglar-alarms, being in the nature of a barricade-alarm for doors, whereby an alarm will be sounded by a partial opening of the door in case any one should attempt to enter when the alarm is set.

15 The invention consists in certain novel constructions and combinations of parts, as will be hereinafter described, and pointed out in the claims.

In the drawings, Figure 1 is a perspective view showing the lower portion of a door with my improvements applied. Fig. 2 is a detail elevation, partly in section, showing the alarm mechanism, the bell being removed. Fig. 3 is a side view of the alarm mechanism. Fig. 25 4 is a top plan view thereof. Fig. 5 is a detail section on about line 5 5, Fig. 2. Fig. 6 is a detail view showing the lower portion of the strut-bar and the seat-plate therefor; and Fig. 7 is a detail view of the seat-plate.

30 In carrying out my invention I prefer to provide the seat-plate A for the lower end of the strut-bar B, such seat-plate being recessed in the floor and having a socket A' for the lower end of the bar B and a hole A² for the bolt B' at the lower end of said bar. While this seat-plate is preferred, it will be understood it may be omitted when desired and the bar be pointed or otherwise adapted at its lower end to engage the floor. At its upper 40 end the strut-bar B has a sliding connection with the door, being preferably provided with a longitudinally-elongated slot B², through which is passed the bolt C, by which the strut-bar is held to the door. This bolt C is supported by lugs or brackets C' on a frame-plate C², which also supports the bell D and the mechanism for sounding the same, which mechanism includes a trip-bar E, arranged for operation by the upper end of the strut-bar and adapted to release the detent which holds the bell from sounding. The alarm

mechanism, as shown in Fig. 1, is supported on the door. This bar E extends above the upper end of the strut-bar, and the latter as it moves upward by the opening of the door 55 will press the bar E up and cause the same to release the detent and permit the bell to sound, as will more fully appear hereinafter. In this operation it will be seen that as the door is opened it will push the upper end of 60 the strut-bar back and the latter will rise, owing to its movement in the arc of a circle with its lower end as a pivot. As it so rises it will lift the bar E and release the alarm mechanism, which I will now describe. 65

The bell is sounded by a spring F, connected with a ratchet F', which is engaged by a detent-pawl G, pivoted at G' and arranged to be engaged by a projection E' on the bar E in such manner as to be released 70 by the upward movement of the strut-bar, as before described. The operation of this construction will be well understood from Fig. 2. As the strut-bar is lifted it will thus release the detent, and the bell will sound; but if 75 the door should be slightly opened and then quickly closed the bell would sound momentarily except for the detent H, which I have provided for holding the bar E elevated when it is pushed up by the strut-bar. As shown 80 in Fig. 5, this detent is in the form of a hook pivoted at its upper end and arranged at its lower end to engage under the bar E when such bar is lifted by the strut-bar. This detent thus holds the bar E up and causes the 85 bell to sound until it is run down or until the detent H is released, so if one should attempt to enter the room and should quickly close the door after the bell commences to sound the bell will not stop ringing, but will continue ringing until run down.

When the strut-bar is not in use, it may be swung upward on the bolt C as a pivot and be held by engaging its bolt B' with an eye or staple I on the door.

Having thus described my invention, what I claim, and desire to secure by Letters Patent, is—

1. A barricade-alarm for doors comprising a strut-bar having at its upper end a sliding 100 connection with the door and an alarm mechanism supported on the door and including

- a trip-bar arranged for operation by the upper end of the strut-bar substantially as set forth.
2. A barricade-alarm for doors, comprising an alarm mechanism adapted to sound the alarm repeatedly and having a trip - bar adapted to release the alarm and a catch or 5 detent for holding said bar when adjusted to release the alarm and a strut-bar for operating the trip-bar substantially as set forth.
3. In an apparatus substantially as described the combination of the door, a strut-bar having at its upper end a sliding connection with said door and the alarm supported 10 independently of the strut-bar and having a trip portion arranged to be released by said strut-bar substantially as described.
4. A barricade-alarm for doors comprising a frame-plate supporting the alarm mechanism and provided with brackets, a strut-bar having a longitudinally-elongated slot and 15 fitted between said brackets, the pin or bolt passed through said slot whereby the strut-bar has a sliding connection with the frame-plate, and the alarm mechanism having a trip portion arranged for operation by the strut-bar substantially as described.
- 20 5. A barricade-alarm for doors comprising the bell, the spring for sounding the bell, the 30 detent-pawl for restraining said spring, the trip-bar arranged at one end to release said 35 detent-pawl, the strut-bar for operating said trip-bar to release the detent-pawl, and a detent for holding said trip-bar when adjusted by the strut-bar substantially as set forth. 35
6. In an alarm mechanism the combination of the strut-bar having at its upper end a sliding connection with the door, alarm mechanism arranged to be released by such upper 40 end of the strut-bar, and a seat-plate to receive the lower end of the strut-bar substantially as set forth.
7. A barricade-alarm for doors, comprising the door, the strut-bar, the alarm mechanism arranged for operation by the strut-bar, a seat-plate in the floor, an eye or staple on the 45 door and a bolt at the swinging end of the strut-bar arranged to engage the seat-plate when the strut-bar is lowered and the eye or staple when the strut-bar is raised substantially as set forth. 50
